Primary Examiner — Ruth McInroy

(74) Attorney, Agent, or Firm — Greenberg Traurig, LLP

(57) **CLAIM**

I claim the ornamental design for a vacuum, as shown and described.

DESCRIPTION

FIG. 1 is a front perspective view of a vacuum showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a rear perspective view thereof.

The details shown in broken lines form no part of the claimed design.
